(57) **CLAIM**

The ornamental design for a wind turbine nacelle, as shown and described.

DESCRIPTION

FIG. 1 is a side view of a wind turbine nacelle in accordance with a first embodiment;

FIG. 2 is a back view thereof;

FIG. 3 is a top view thereof;

FIG. 4 is a front perspective view thereof;

FIG. 5 is a front perspective view of the wind turbine nacelle of the first embodiment shown in environmental use;

FIG. 6 is a side view of a wind turbine nacelle in accordance with a second embodiment;

FIG. 7 is a back view thereof;

FIG. 8 is a top view thereof;

FIG. 9 is a front perspective view thereof;

FIG. 10 is a front perspective view of the wind turbine nacelle of the second embodiment shown in environmental use;

FIG. 11 is a side view of a wind turbine nacelle in accordance with a third embodiment;

FIG. 12 is a back view thereof;

FIG. 13 is a top view thereof;

FIG. 14 is a front perspective view thereof; and,

FIG. 15 is a front perspective view of the wind turbine nacelle of the third embodiment shown in environmental use.

The portions shown in dashed lines in the figures are for environmental purposes only and make up no part of the claimed design.
